UNITED STATES PATENT OFFICE

LUDWIK KUDZIA, OF JARACZEW, POLAND

SNOWPLOW FOR ENGINES

Application filed June 21, 1928. Serial No. 287,065.

This invention relates generally to snow plows, the invention having more particular reference to a novel type of snow removing apparatus especially adapted to be attached to locomotives for removing snow from the tracks.

The invention has for an object the provision of an improved snow plow which will act more efficiently in removing the snow from the tracks.

A further object is to provide a device which may be attached to the locomotive, which will render the use of individual snow plows, such as now commonly used, unnecessary.

A further object is to provide a device of this nature of simple construction and novel arrangement of parts.

For further comprehension of the invention, and of the objects and advantages thereof, reference will be had to the following description and accompanying drawing, and to the appended claims in which the various novel features are more particularly set forth.

Fig. 1 of the drawing, shows my improved device attached to a locomotive, as it would appear when ready for operation.

Fig. 2 shows a detail top plan view of my improved device.

Fig. 3 shows a side elevational view of my improved device.

The reference numeral 10 indicates generally a locomotive of any design, resting on tracks 11, and having a customary cow-catcher 12. A base plate 13 has a plurality of slots 14 for the engagement of bolts to attach the base to the cow-catcher 12. The base plate 13 is provided with standards 15 adjustably connected so as to be raisable and lowerable relative thereto. A sub-frame 16 is pivotally connected to the standards 15.

Propellers 17 are rotatively mounted in the sub-frame 16, and are directed in front of the locomotive 10. Bevel gears 18 are secured to the propeller shafts and mesh with

gears 19 on shafts 20 rotatively mounted in the frame 16. An electric motor 21 is mounted on the sub-frame 16 and connected to drive shafts 20, so that the propellers 17 rotate.

A motor driven air blower 22 is mounted on the base 13, and discharge pipes 23 lead therefrom to the vicinity of the propellers 17, and are there supported by brackets 24 projecting from the sub-frame. Air discharged thru these pipes aids the propellers in cleaning the tracks.

An arm 25 projects from the sub-frame 16, being slidably arranged in groove 26 and having a setting bolt 27 extending from a slot 28 communicating with the groove 26, so as to be lockable at various distances from the pivot point of the sub-frame 16. A rod 29 connects with the arm 25 and with a second arm 30 on shaft 31 supported by standards 32 projecting from the cow-catcher 12. A third arm 33 connects with shaft 31, and rod 34 connects this arm with a bellcrank 35 pivoted to locomotive 10. A string 36 connects with the free end of the bellcrank 35, slidably passes thru a bracket 37, and has a head 38 attached to its top end. The bracket 37 is threaded to a screw 39 rotatively supported to the side of the locomotive. A U-shaped bracket 40 is positioned above the bracket 37 and threaded to a screw 41 rotatively mounted on the side of the locomotive.

The rear ends of the standards 15 are formed with tongues 42 vertically slidable in grooves in the base 13. Integral with the tongues 42 are rack teeth 43 engaged by pinions 44 rotatively mounted in the base 13, being fixed on shafts 45 having enlarged ends 46 for engagement with a turning tool. Latches 47 are slidably mounted in the base 13 and urged by spring 48 into engagement with the teeth of the pinions to lock same against rotation.

In operation, the motor 21 drives the propellers 17, and the motor driven air blower feeds air thru the pipes 23. The head 38

rests against the bracket 37 and holds the sub-frame 16 in one position. The head 38 may be lifted and engaged in the U-shaped bracket 40 to lift the sub-frame 16, obviously raising propellers 17. The arm 25 may be adjusted at different distances from the pivot point of the sub-frame, to change the height to which the sub-frame is lifted. The screws 39 and 41 may be turned to adjust the positions of the brackets 37 and 40. The latches 47 may be moved and then the pinions 44 turned to adjust the height of the sub-frame 16.

While I have shown and described a preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Patent is:—

1. A device of the class described, comprising a base, standards adjustably connected to the base, a sub-frame pivotally connected to the standards, propellers and driving means mounted on the sub-frame, an arm projecting from the sub-frame, means for adjusting the distance of the arm from the pivot point of the sub-frame, linkage connected to the arm, a cord connected to the linkage, a bracket slidably holding the cord, a head on the cord resting against the bracket, said bracket being adjustably mounted, and a U-shaped bracket positioned above said bracket and also adjustably mounted, the head on the cord being liftable to engage the U-shaped bracket so to raise the sub-frame.
2. A device of the class described, comprising a base, standards adjustably connected to the base, a sub-frame pivotally connected to the standards, propellers and driving means mounted on the sub-frame, an arm projecting from the sub-frame, means for adjusting the distance of the arm from the pivot point of the sub-frame, linkage connected to the arm, a cord connected to the linkage, a bracket slidably holding the cord, a head on the cord resting against the bracket, said bracket being adjustably mounted, and a U-shaped bracket positioned above said bracket and also adjustably mounted, the head on the cord being liftable to engage the U-shaped bracket so as to raise the sub-frame, and the means for adjustably mounting the said brackets consist of screws rotatively mounted and threadedly engaging the brackets.
3. A device of the class described, comprising a base, standards adjustably connected to the base, a sub-frame pivotally connected to the standards, propellers and driving means mounted on the sub-frame, an arm projecting from the sub-frame, means for ad-

justing the distance of the arm from the pivot point of the sub-frame, linkage connected to the arm, and terminating in a pivoted bell-crank, a cord connected to the bellcrank, a bracket slidably holding the cord, a head on the cord resting against the bracket, said bracket being adjustably mounted, and a U-shaped bracket positioned above said bracket and also adjustably mounted, the head on the cord being liftable to engage the U-shaped bracket so as to raise the sub-frame.

In testimony whereof I have affixed my signature.

LUDWIK KUDZIA.
